HEAT EXCHANGE EQUIPMENT

James M. Jenkins, Philadelphia, Pa., assignor to
Andale Company, Philadelphia, Pa., a corpora-
tion of Pennsylvania

Application March 19, 1938, Serial No. 196,865

2 Claims. (Cl. 257—224)

This invention relates to heat exchange equipment and especially to a heat exchange unit of the tube and shell type.

The invention is more particularly concerned with a tube sheet arrangement in which two tube sheets are employed adjacent an end of the tube bundle, the two tube sheets being secured to each other and providing a venting space therebetween.

According to the invention, provision is made for exposing to the shell space a substantial area not only of the inner tube sheet but also of the outer tube sheet, this being of importance for reasons pointed out more fully hereinafter, although at this time it is noted that the arrangement is of substantial advantage in reducing leakage around the tubes, especially at the inner tube sheet, as has occurred at times in various installations, particularly where very high temperatures are encountered.

20 How the foregoing objects and advantages are attained will appear more fully in the following description making reference to the accompanying drawing illustrating a preferred embodiment of the invention.

25 In the drawing, a heat exchanger shell is designated by the numeral 1, this shell conveniently being of cylindrical shape and having inlet and outlet connections 2 and 3 adjacent opposite ends thereof. A tube nest incorporating a plurality of tubes 4 extends lengthwise through the shell, and at the two ends of the tube nest 1 preferably provide inner tube sheets 5 and 6 and outer tube sheets 7 and 8. The outer tube sheet 8 at one end of the unit (the upper end in the drawing) carries a header 9 secured thereto as by studs 10, this header serving as the inlet header and having an inlet connection 11. Corresponding outlet header parts 12, 13 and 14 are carried by the outer sheet 7 at the other end of the unit.

30 The shell, tubes, headers and connections thus provide for counterflow of two fluids in heat exchange relation, one through the shell and the other through the tubes, the shell space, if desired, being baffled as by means of plates 15 ar-
45 ranged in any convenient manner to provide a sinuous path through the shell.

At one end of the unit (the lower end in the drawing) the outer tube sheet 7 is of larger diameter than the shell and is bolted to a securing ring 16 as at 17. The inner sheet 5 at this end is of substantially smaller diameter than the inside diameter of the shell and is provided with a peripheral ridge 18 seated against the inner face of the outer sheet, the two sheets preferably being welded together by a joint 19. This ar-

rangement provides for securing the sheets together in spaced relation to provide an intersheet space 20 having a vent passage 21 to the exterior of the unit through the outer sheet 7.

At the other end of the unit the outer sheet 8 is preferably of such diameter as to fit into the shell in order to permit freedom for relative expansion and contraction of the tubes and shell. A flexible bellows joint 22 is secured at one edge 23 to the shell and at its other edge to a ring 24 which may be bolted to the outer face of the outer sheet 8 as by studs 25.

The inner sheet 6 at this end is arranged in a manner similar to that described in connection with sheet 5, i. e. is provided with a peripheral rib 26 welded to the sheet 8 at 27, the sheet 8 also being provided with a vent passage 28 communicating with the inter-sheet space.

In considering the operation and advantages of the structure described, attention is first directed to the fact that the multiple tube sheet arrangement provides a number of important advantages mentioned herebelow, although it is pointed out that the employment of two tube sheets broadly is not a part of the present invention per se. The advantages in question include provision for venting of any leakage which may occur around the tubes through either of the tube sheets, thus, either from the shell space or from the header space. The two sheets vented in this manner also prevent intermingling of the two fluids, as would result upon leakage around the tubes in a unit employing only a single tube sheet. Still further, the double tube sheet arrangement makes possible introducing air or other fluid under pressure into the inter-sheet space for the purpose of testing the tube joints in both sheets. If desired, the vent passages for the inter-sheet spaces may be threaded at their outer ends for coupling with piping for the purpose of carrying away any leakage, to a point remote from the equipment or exteriorly of the building in which it is housed.

The present invention attains not only these advantages but further overcomes certain disadvantages encountered in prior units employing double tube sheets.

The point in question may be considered to best advantage when bearing in mind that units of this type are frequently employed, for instance in chemical industries, in situations where one or the other or both of the fluids are at very high temperature. In certain prior arrangements the high temperatures have resulted in irregular expansion and contraction of the two sheets with

consequent non-uniform stresses as between the two sheets. Irregularity of heating of the two tube sheets has resulted from arrangement or disposition of the sheets in such manner that only one of them is exposed to the shell space, or that the outer one is subject to substantial cooling, or both.

To overcome these difficulties, the present invention provides for substantial exposure of both 10 of the tube sheets to the shell space. This is effected by securing or joining the outer of the two sheets to the shell and by making the inner sheet 15 of a diameter considerably less than the inside diameter of the shell, whereby to expose a substantial annular area of the inner face of the outer sheet to the shell space. In consequence, contact of the fluid in the shell space effectively heats both of the tube sheets, the heat in the outer sheet being readily transmitted by conduction from the exposed annular area to all 20 parts thereof.

The foregoing substantially eliminates difficulties arising from the sources discussed above since it provides for approximately uniform 25 stresses in the two tube sheets, the tube joints in the sheets in consequence remaining tight and preventing leakage. This is accomplished moreover without sacrificing any of the important advantages of the double tube sheet arrangement.

30 I claim:

1. In a tube and shell heat exchanger, a tube sheet at an end of the shell joined to said end to close the shell space, a second tube sheet positioned at the inner face of the first sheet with a venting space therebetween, heat exchange tubes each extended through the venting space and each having a fluid tight joint in each of said sheets, the two sheets being in engagement with each other substantially only in a narrow zone surrounding said venting space, the first tube sheet having a substantial area of its inner face exposed to the shell space, and means for venting said venting space.

2. In a tube and shell heat exchanger, a tube sheet at an end of the shell, a second tube sheet 15 of smaller diameter positioned at the inner face of the first sheet with a venting space therebetween, a nest of heat exchange tubes each extended through said venting space and each having a fluid tight joint in each of said sheets, the 20 venting space being peripherally closed adjacent the edge of the tube sheet of smaller diameter, and the first tube sheet being joined to the shell radially outwardly of the edge of the second tube sheet to provide for exposure of a substantial 25 area of the inner face of the first tube sheet to the shell space, and means for venting the venting space exteriorly of the spaces in communication with the shell and tubes.

30 JAMES M. JENKINS.
